UNITED STATES PATENT OFFICE

2,590,683

TUNNEL LINING FORM

Ralph E. Clapp, Spokane, Wash.

Application February 21, 1949, Serial No. 77,533

1 Claim. (Cl. 25—131.5)

1

This invention relates to lining tunnels with concrete held in place by improved forms while drying and setting.

At the present time it is customary to line tunnels with concrete but due to the methods used and the forms employed it is not possible to use the tunnels while they are being lined or portions of a lining replaced.

An object of the invention is to provide an improved arch forming form so constructed that it may be easily erected and firmly supported upon frames anchored to linings previously applied to opposite side walls of a tunnel.

Another object of the invention is to provide an arch-forming form which is braced against collapsing and may serve as a carrier for scaffold boards for use by workmen during application of concrete to form the arch of a tunnel.

Another object of the invention is to provide improved arch-forms which are strong and not liable to be broken by the weight of concrete applied to the walls and the arch or top of a tunnel.

The invention is illustrated in the accompanying drawings wherein:

Fig. 1 is a transverse sectional view of wall linings formed with forms of the improved construction.

Fig. 2 is a transverse sectional view showing an arch-forming form of the improved construction supported in position for use.

Fig. 3 is a fragmentary sectional view upon an enlarged scale showing the manner in which sides of the arch-forming form are connected with supporting frames.

Fig. 4 is a fragmentary view in elevation of a wall-forming form, braces for the same being in section.

Fig. 5 is a sectional view taken vertically through Figure 2.

The tunnel 1 illustrated in the accompanying drawings represents a railroad tunnel through which a single track 2 has been laid upon a road bed 3; but it will be understood that other specific types of tunnels may be lined by use of the improved forms and in accordance with the improved method. A footing or base 4 of concrete is laid along opposite sides of the bottom of the tunnel and each has a ledge or shoulder 5, the upper face of the base being formed with a longitudinally extending groove or key way 6. After the footings or bases have dried and hardened wall forms 7 are erected upon boards 8 laid along the shoulders, and since these wall forms are provided with rollers 9 they may be easily

2

shifted along the bases longitudinally of the tunnel from one place to another as the walls of the tunnel are lined with concrete. Before the wall forms are set up in spaced relation to the walls of the tunnel a suitable number of holes 10 are formed in the walls and into these holes are driven lead fillers 11 which receive anchoring bolts 12. The bolts are of such length that they extend through the wall liners 13 formed of concrete poured into spaces between the forms and the side walls of the tunnel. The forms are secured to the anchor bolts in order to maintain them in a perpendicular position and after the concrete has set the forms are detached from the bolts and shifted along the footings to an advanced position where another section of wall lining is formed. Portions of the concrete form ribs 14 which fit into the key ways or grooves 6 and prevent the liner from shifting transversely of the footings and upper edge faces of the liners are formed with grooves or key ways 15. While the newly poured concrete is setting frames 16 are erected upon the ledges of the footings and anchored to the upper anchor bolts 12. A transversely arcuate arch-forming form 17 is then erected upon the frames and space between this form and the arch or top of the tunnel filled with concrete which is supported by the arch form until it has set and hardened to form the arch liner 18 which has its side edge faces formed with tongues 19 fitting into the grooves 15 of the wall liners to establish interfitting engagement between sides of the arch liner and upper ends of the wall liners. It will thus be seen that after a tunnel has been provided with wall liners for a portion of its length the wall forms may be shifted along the tunnel to an advanced position for forming additional wall liner sections and the wall liner sections formed in step by step movements of the wall forms, the arch sections being also formed by step by step movements of the arch form and each arch section formed while wall liner sections in advance of it are being poured and allowed to set. This saves time in the formation of a complete liner for a tunnel and as the forms do not obstruct the tunnel trains, vehicles, and other traffic may have use of the tunnel while the tunnel is being lined.

The wall-forming forms are of duplicate construction and each of rectangular shape, the height being such that it will extend from the shoulder 5 to the junction of a side wall of the tunnel to the adjoining side or the arch of the tunnel. The length of each wall form is sufficient to allow a liner section 13 of appreciable length

to be formed but also of such length that the form may be conveniently shifted to an advanced position after a liner section has dried. Studdings 20 extend vertically in transverse spaced relation to each other and have their ends secured to upper plate 21 and lower sill 22. To the studdings and the timbers are secured sheets of plywood or other material to form a facing 23 disposed in confronting relation to the wall of the tunnel so that when concrete is poured into space between the tunnel wall and the wall form and allowed to dry and set the wall lining 13 formed thereby will have a smooth surface. Timbers 24 are secured against the studdings and extend longitudinally of the form in vertically spaced relation to each other and in downwardly spaced relation to the lowest timber is mounted a stringer or rail 25 of less thickness than the timbers 24. The timbers 24 are bored to form a plurality of openings 26 which are spaced from each other longitudinally of the timbers, and through each opening passes a bolt or rod 27 having its inner end portion formed with a threaded socket 28 to receive a companion one of the anchor bolts 12 and its outer end portion threaded to receive a nut 29. These bolts are of the same construction as the bolts shown in Figure 3 for securing the frames 16, it being understood that bolts of modified construction may be used provided they are adapted for threaded connection with the outer ends of the anchor bolts 12. Braces 30 and 31 extend from the lower sill 22 and the rail 25 to a beam or stringer 32, and cooperate with each other to form braces 33, the length of the braces being such that the stringer may have contact with ends of the ties 34 of the track 2. After the concrete has set the bolts 27 are removed and also the braces 33 and a temporary brace 35 indicated by dotted lines in Figure 1 applied so that the temporary braces which rest upon the rails 36 of the track will support the forms upright while they are being moved upon the rollers 9 along the boards 8 to an advanced position in the tunnel where they will be connected with other anchoring bolts projecting from the walls of the tunnel and concrete poured to form additional lining sections.

The frames 16 which support the arch form 17 are mounted upon the boards 8 after the wall forms have been shifted forwardly. Each of these frames has vertically disposed studdings 38 having their upper ends secured to a stringer 39 and their lower ends secured to a sill 40. The studdings are braced by diagonally extending braces 41 and against upper end portions of the studdings is secured a beam 42 through which additional bolts 27 pass for engagement with outer ends of the upper ones of the anchoring bolts 12. Blocks 43 and companion wedges 44 upon which the frame rests support the frame at such a distance above the board 8 that the bolts may be readily screwed into engagement with the anchoring bolts and also allow the bolts to be easily removed when the frames are to be taken down or shifted forwardly to advanced positions. The frames will therefore be securely held upright and in spaced relation to the exposed surfaces of the wall linings 13. The arch-forming form 17 which is supported upon the frames has a plurality of bridges or arches 45 having ribs or sections 46 nailed in staggered and side by side relation to each other, inner or upper ones of these sections being spaced from each other and connected by a key-section 47. Flanks 48

are secured to the bridges to form a solid skin for the arch form. The space 49 is closed by applying the key-section 47 or plank. A number of blocks 50 are applied between the arch center 5 and ceiling of the tunnel to prevent weight of the concrete from bulging the bridges and the skin out of a true arcuate shape transversely of the tunnel. The thickness of the planks is the same as the space between the frames 16 and 10 the wall linings 13 and the upper ends of these spaces will therefore be closed and leakage of concrete from the arch form prevented. It will thus be seen that when the lining for the arch has set its outer surface will merge into the outer 15 surfaces of the wall linings. Ends of the bridges are secured to sills 51 and end ones of the ribs 46 are formed with ears 52 projecting downwardly and are formed with openings registering with openings formed in rails 53 so that lag screws 20 54 may be applied and securely hold the side portions of the arch form to the supporting frames. Brackets 55 which straddle the end ones of the bridge sections project inwardly of the arch form and with these brackets are engaged 25 removable rods 56 connected by a turn buckle 57. The rods break the form from the set concrete before moving them to the next section to be poured. U-shaped hanger brackets 58 extend downwardly from side portions of the bridges and 30 support timbers 59 which extend longitudinally of the tunnel and beyond the end of the arch form and constitute supports for scaffold planks 60 upon which workmen may stand while filling space between the arch form and the top of the 35 tunnel.

Concrete is applied from the end of the arch form through pipes and is evenly filled on each side of the form to maintain an equal pressure on the form sides. A bulkhead is applied to the 40 open end of the arch form to contain the concrete in the proper area. When this space is nearly filled with concrete, the weight thereof causes the form to settle slightly whereupon blocks 50 may be easily removed, and the balance 45 of the space filled with concrete.

After the cement has set, turnbuckle 57 is actuated to draw rods 56 inwardly thus pulling the sides of arch 17 free from the set concrete. Wedges 44 and blocking 43 are then removed allowing the frames and arch to lower onto rollers or dollies whereupon it may be moved to the next section to be poured, and again raised into position.

When the cement work is entirely finished, key-section 47 is removed and the horizontal ribs in the top center of the arch unbolted allowing the arch form to be lowered in two sections providing for ease in handling while transporting to another tunnel job.

Having thus described the invention, what is claimed is:

Apparatus for forming a lining for the arch of a tunnel comprising frames adapted to be mounted upright in confronting relation to lined 55 walls of a tunnel, and a form adapted to be supported upon said frames and including bridges extending transversely of the form and spaced from each other longitudinally of the form and having depending ears at their ends overlapping 60 upper portions of the frames, fasteners for detachably connecting the ears at ends of said bridges with upper portions of said frames, planking extending longitudinally of the forms and secured against outer edge faces of said bridges for supporting concrete in space between

the form and the arch of the tunnel, U-shaped hangers depending from said bridges in upwardly and inwardly spaced relation to their ends, beams extending longitudinally of said form and passed downwardly through and thereby supported by said hangers, scaffold boards extending transversely of the form and having opposite ends resting upon and supported by said beams, brackets mounted horizontally in straddling relation to end portions of said bridges and having ends projecting horizontally therefrom inwardly of the form, and rods extending transversely across the form between ends of said bridges and having hooks at their ends engaged with the projecting ends of said brackets, and turnbuckles threaded upon inner ends of said rods for adjusting the rods longitudinally and holding their hooks in firm engagement with the brackets.
